US00D841399S

(12) **United States Design Patent** (10) **Patent No.:** **US D841,399 S**
(45) **Date of Patent:** **** Feb. 26, 2019**

(54) **HYDRATION BLADDER**

(71) Applicant: **Shock Doctor, Inc.**, Minnetonka, MN (US)

(72) Inventors: **Adam Peter Karl, IV**, Burlington, VT (US); **Benjamin Casey Lanza**, Sheldon, VT (US); **James Creath Frazier**, Hinesburg, VT (US); **Bradley Philip Fishkin**, Burlington, VT (US); **Faith LeAnn Piotrowski**, Warminster, PA (US)

(73) Assignee: **Shock Doctor, Inc.**, Minnetonka, MN (US)

(**) Term: **15 Years**

(21) Appl. No.: **29/612,642**

(22) Filed: **Aug. 2, 2017**

Related U.S. Application Data

(62) Division of application No. 29/566,912, filed on Jun. 3, 2016, now Pat. No. Des. 796,903.

(57) **CLAIM**

The ornamental design for hydration bladder, as shown and described.

DESCRIPTION

FIG. 1 is a front perspective view of a hydration bladder illustrating our new design in an unfilled state;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a front perspective view of the hydration bladder illustrating our new design in a filled state;

FIG. 9 is a front view thereof;

FIG. 10 is a back view thereof;

FIG. 11 is a left side view thereof;

FIG. 12 is a right side view thereof;

FIG. 13 is a top view thereof; and,

FIG. 14 is a bottom view thereof.

The broken lines in the drawing views represent environmental structure and form no part of the claimed design.

1 Claim, 12 Drawing Sheets
